(57) **CLAIM**

The ornamental design for a diffusing nozzle for a hair-dryer, as shown and described.

DESCRIPTION

FIG. 1 is a front, top perspective view of a diffusing nozzle for a hair-dryer, showing my new design;
 FIG. 2 is a front, right side perspective view thereof;
 FIG. 3 is a rear, bottom perspective view thereof;
 FIG. 4 is a front elevation view thereof;
 FIG. 5 is a rear elevation view thereof;
 FIG. 6 is a left side elevation view thereof;
 FIG. 7 is a right side elevation view thereof;
 FIG. 8 is a top plan view thereof; and,
 FIG. 9 is a bottom plan view thereof.

The broken lines in the figures illustrate portions of the diffusing nozzle for a hair-dryer that form no part of the claimed design.
